UNITED STATES PATENT OFFICE.

JAMES R. MONTGOMERY, OF FRANKFORT, KANSAS.

COAL-CLEANER.

1,140,999.

Specification of Letters Patent. Patented May 25, 1915.

Application filed May 25, 1914. Serial No. 840,807.

To all whom it may concern:

Be it known that I, JAMES R. MONTGOMERY, a citizen of the United States, residing at Frankfort, in the county of Marshall and State of Kansas, have invented certain new and useful Improvements in Coal-Cleaners; and I do declare the following to be a full, clear, and exact description of the invention, such as will enable others skilled in the art to which it appertains to make and use the same.

This invention relates to improvements in coal cleaning apparatus.

The object of the invention is to provide a portable coal screening apparatus especially designed for the use of local coal dealers for screening out coal before sending it to a customer so as to deliver it in a clean condition free from dust.

Another object of the invention is to provide simple and efficient apparatus of this character by means of which coal may be simultaneously screened and loaded from a bin into a vehicle.

Another object is to provide an apparatus of this character so constructed as to protect the operator and surrounding atmosphere from the dust produced by the screening operation.

With these and other objects in view, the invention consists of certain novel features of construction, combination and arrangement of parts as will be more fully described and claimed.

In the accompanying drawings: Figure 1 is a longitudinal vertical section thereof; Fig. 2 is a transverse section, and Fig. 3 is an end elevation thereof.

In the embodiment illustrated, a suitably constructed truck 1 is shown on which is mounted a closed casing 2 preferably composed of heavy galvanized iron and of any suitable or desired size. When possible, the power for operating the screening apparatus is to be furnished by a motor 3 mounted on the truck and which may be electric or of any other desired construction provided that it be as light as possible as the apparatus is designed to be moved from one coal bin to another as required.

Extending downwardly at an oblique angle from the upper end of the casing 2 is a conveyer 4 inclosed in a casing and similar to those used on corn shellers. This conveyer casing is preferably made in foldable sections 5 and 6 and the free end of the

outer section 6 is designed to extend back into a bin and is provided with a hopper 7 to receive the coal to be screened. The free end of this conveyer casing section 6 is preferably supported by adjustably mounted uprights 8 here shown slotted longitudinally at 9 and engaged with the walls of the conveyer chute or casing by means of set screws 10 whereby said supports may be adjusted to adapt the device to coal bins of different heights. When the section 6 is folded on the section 5 these uprights are turned up and form a support for engaging the fixed member 5 of the conveyer casing and form a support therefor. This conveyer 4 is shown mounted in the closed casing and comprises an endless belt, the stretches thereof being adjustable by means of a screw 11 to provide for the tightening or loosening thereof as 75 may be desired, the conveyer being loosened when the sections of the casing thereof are to be folded.

A small opening 12 is provided at the lower end of the conveyer casing section 6 for letting out any dust or small pieces of coal which might hang to the chains as they pass downward. This conveyer casing is preferably provided with a partition 13 on which the upper stretch of the conveyer is 85 designed to travel. This conveyer is driven by an endless belt 14 connected with the motor 3 and shown clearly in Fig. 1, and is adapted to conduct the coal thrown into the hopper 7 upward and discharge it into 90 the upper end of the casing 2 onto a suitably disposed screen 15 which is arranged at an inclination being inclined downwardly from the end on which the coal is discharged to a discharge pipe 16 arranged at the opposite side of the casing 2. This pipe or chute 16 is placed in position to adapt it to extend over the body of an ordinary coal wagon or cart. The screen 15 is preferably constructed with a frame made removable to 100 adapt it to be interchanged for a screen of different mesh when desired.

Arranged over the spout 16 is an outwardly swinging door 17 adapted to be opened by the lumps of coal passing from 105 the screen into the chute 16 and which is designed to retain as much dust as possible within the casing 2 and to assist a fan to be described in its work.

Arranged below the screen 15 are two 110 slanting dust guiding members 18 and 19 which converge toward their lower ends and

are spaced apart as shown at 20 and at one end thereof is arranged a fan 21. At the opposite end of these members in alinement with the fan 21 is an upwardly extending 5 dust discharging pipe 22 provided at its free end with an adjustable hood 23 which may be regulated to discharge the dust at any desired angle.

A door 24 is formed in one wall of the 10 casing 2 in the form of a scoop board and is designed to be let down for the removal of any screenings which may fall to the bottom of the casing and which may be sold at the usual figure.

15 As shown, the fixed member 5 of the conveyer casing is supported by uprights 5' which project upwardly from one end of the truck 1 and are secured to opposite sides of the casing near its hinged end for affording a firm support for the conveyer when in operation.

In the use of this improved apparatus, the truck 1 is first moved in proximity to the bin from which it is desired to transfer the 20 coal to be screened and the hinged section 6 is then opened downwardly and positioned with its free end extending into the bin. The operator then shovels coal into the hopper 7 which falls onto the conveyer 4 and is 25 conducted upwardly and discharged onto the screen 15 of the casing 2 which is so inclined as to cause the coal to pass downwardly thereover at a slow rate of speed sufficient to cause the dust contained therein 30 to pass through the mesh of the screen and drop down onto the dust guiding members 18 and 19 and the coal to pass out through the chute 16.

After the slack and dust falls onto the 35 screening members 18 and 19 it is directed toward the space 20 where the draft from the fan 21 strikes it and drives it across the casing 2 and out through the discharge pipe 22. This discharge pipe 22 is hingedly connected with the casing 2 and is adapted to 40 be raised and lowered as required by a cable 25 and ratchet 26 which holds the cable in adjusted position after the pipe has been disposed at the desired inclination.

50 The fan 21 may be equipped with any desired number of blades and is made large enough to produce a draft sufficient only to

remove the dust without blowing any of the screenings into the pipe 22 as these screenings can always be disposed of at some figure 55 and they are designed to fall below into the bin or casing 2 and to be removed as required through the opening closed by the door 24.

It may here be explained that the plates 60 18 and 19, although being inclined downwardly and inwardly from two sides of the casing 2, lie approximately in a horizontal plane, this being advantageous in order that coal dropped on said plates, will be suddenly checked, thus effectively jarring all dust from this coal. The blast created longitudinally between the edges of these plates by the fan 21, will now sweep over the upper inner edge portions thereof, thereby blowing 65 all of this dust out through the discharge 70 20, while the heavier particles of coal will roll downwardly upon the inclined plates and will be discharged therefrom into the bottom of the casing. In so falling from these 75 plates, the coal is again and more forcibly subjected to the current of air, whereby it will be thoroughly cleaned. The strength of this blast of air, may be so regulated as to cause it to force all of the coal into the 80 rear side of the casing away from the door 24, this being obviously an advantage.

I claim as my invention:

A coal cleaning machine comprising an upright casing, means at the top thereof for dropping coal therein, and a transverse plate near the inner end of the casing inclining downwardly and from one side thereof, said plate lying approximately in a horizontal plane whereby to suddenly check the downward movement of coal dropped thereon, thus jarring all dust from this coal, combined with means whereby a blast of air may be projected longitudinally of the inner edge of said plate and over the upper inner edge 90 portion thereof.

In testimony whereof I have hereunto set my hand in presence of two subscribing witnesses.

JAMES R. MONTGOMERY.
